UNITED STATES PATENT OFFICE

NICHOLAS E. NICOLET, OF NEW YORK, N. Y.

SCORING DEVICE

Application filed October 8, 1931. Serial No. 567,528.

This invention relates to improvements in scoring devices and has particular reference to a device employed in the game of contract bridge.

5 An object of the invention is to provide an improved device of simple and practical construction which may be incorporated in a pencil or pen and thus provide a convenient means of readily ascertaining and recording 10 a score.

Another object is to mount a sleeve-like element upon a member having a cylindrical surface which bears scoring indicia visible through sight openings in said sleeve, with 15 one of said elements rotatable relative to the other to register different portions of said indicia with said openings.

The above and other objects will appear more clearly from the following detailed 20 description, when taken in connection with the accompanying drawings, which illustrate a preferred embodiment of the inventive idea.

In the drawings—

Figure 1 is a side elevation of the scoring 25 device constructed in accordance with the invention;

Figure 2 is a longitudinal section there- 30 through; and

Figure 3 is a section on the line 3—3 of Figure 2.

The invention is shown in its adaptation to a pencil of the magazine type in which the lead is adjustable, but it will be understood, of course, that the idea involved may be incorporated in a fountain pen or like device without departing from the spirit or scope of the invention. The pencil illustrated comprises the tip 5 forming one of the end members thereof and containing the lead which 35 is projected or retracted in the usual manner by a turning movement of said tip. Mounted between the tip 5 and the second end member 6 is an inner member 7 of tubular form and presenting a cylindrical surface. An outer 40 sleeve-like member 8 encloses the member 7, one of said members having a rotary movement relative to the other. In the present embodiment, the outer member 8 is rotatable about the member 7 for a purpose which will 45 appear in the course of the description.

The device is especially, though not necessarily, adapted for use in scoring the game of bridge, and particularly contract bridge in which the calculation for total scores is sometimes difficult even for experienced players. 55

In carrying out the invention, the cylindrical surface of the inner member 7 is provided with indicia giving the total scores for various situations arising in the bidding of contract bridge and, by turning the sleeve 60 8 to the proper position for any given situation, the score therefor is made visible on the member 7 through elongated sight openings 9 and 10 formed in the outer member 8, as shown in Figure 1. The sight opening 9 is 65 associated with such scores as relate to the invulnerable position of the partners making the bid, while the opening 10 discloses the scores when said partners are vulnerable, as indicated by the words "invulnerable" 70 and "vulnerable" along the upper edges of the respective openings. There are three circumferential rows of Figures 11, 12 and 13 visible through the opening 9 and the figures in these rows indicate the scores when the 75 contract is not doubled, doubled, or redoubled, respectively, as indicated by the designations "nd", "d" and "rd" along the lower edge of the opening 9. Likewise, three rows of figures 14, 15 and 16 on the member 80 7 designate different scores for a vulnerable partnership when the contract is not doubled, doubled, or redoubled, respectively.

All of these rows of figures give the scores 85 for either extra tricks made over and above the contract by the bidding side, or under tricks lost when the contract is defeated. In order to determine the scores for the extra or under tricks, two means are shown, one 90 of which may afford a check against the other. One of said means comprises a circumferential row of figures 17 on the member 7 at the center thereof and between the other rows of figures mentioned, said row 95 of figures being visible through a sight opening 18 formed in the sleeve member 8 between the openings 9 and 10. The row of figures 17 comprises two groups, one of which contains the numbers 1 to 6 for extra tricks and 100

the other group the numbers 1 to 7 for under tricks.

Thus, for example, if a contract is made by the bidding side and five tricks over and above said contract are made, the score for said extra tricks may be determined by turning the member 8 until the numeral 5 of the group assigned to extra tricks in the row 17 is registered with the eight opening 18 (Figure 1). The score for said extra tricks may then be determined through either the opening 9 or 10, depending upon the invulnerable or vulnerable condition of the side making the bid and the state of said bid, that is, whether the same has not been doubled, or otherwise. As a further means of determining the score, the tip 5 is provided at its inner end with a circumferential row of figures 19 divided into groups in the same manner as the row 17, one of the groups being designated by the words "under tricks" and the other by the words "extra tricks". Extending from each one of the figures of said row 19 are the lines 20 and on the end 25 of the sleeve 8 adjacent the tip 5 the former is provided with an indicator 21. By turning the sleeve until said indicator registers with one of the lines 20 extending from the desired number of the row 19, the openings 30 9 and 10 are brought into proper alignment with the desired sets of scores 11 to 16 and the number of the row 17 visible through the opening 18 corresponds to the number of the row 19 that is opposite the indicator 21.

35 What is claimed is:

A scoring device for use in playing the game of bridge, comprising an inner member having a cylindrical surface bearing two groups of circumferential rows of figures indicating various honor and penalty totals obtained under different conditions of play, the figures of each circumferential row being longitudinally aligned with certain figures of the other rows to form horizontal groups, 45 another single circumferential row of figures on said surface indicating extra and under trick values in either of the two first mentioned groups of figures, each figure of said row being longitudinally aligned with figures 50 of the first-mentioned rows, and an outer sleeve-like member rotatable on said inner member and having longitudinally aligned elongated openings through either of which all of the figures in any horizontal group of 55 the associated circumferential rows are visible, and further having another opening aligned with said elongated openings and through which is visible said single circumferential row of figures.

60 In testimony whereof, I have affixed my signature.

NICHOLAS E. NICOLET.
